(57) **CLAIM**

The ornamental design for the combination ceiling fan and light fixture, as shown and described.

DESCRIPTION

FIG. 1 is a perspective view from below of the combination ceiling fan and light fixture in accordance with my design;

FIG. 2 is a reduced top plan view of the combination ceiling fan and light fixture in accordance with my design;

FIG. 3 is a reduced bottom plan view of the combination ceiling fan and light fixture in accordance with my design;

FIG. 4 is a side elevation view of the combination ceiling fan and light fixture in accordance with my design; and,

FIG. 5 is a front elevational view of the combination ceiling fan and light fixture in accordance with my design.

The right and left elevation views are identical except for positioning of the fan blades.

The front and back elevation views are identical except for positioning of the fan blades.

The broken lines showing environmental structure are for illustrative purposes only and form no part of the claimed design.
